(57) **CLAIM**

The ornamental design for a block set for construction of structures, as shown and described.

DESCRIPTION

FIG. 1 is a perspective view of a front of a first block of a block set for construction of structures showing the claimed design;

FIG. 2 is back perspective view of the first block;

FIG. 3 is a front view of the first block;

FIG. 4 is a back view of the first block;

FIG. 5 is a side view of the first block;

FIG. 6 is a side view of the first block;

FIG. 7 is a top view of the first block;

FIG. 8 is a bottom view of the first block;

FIG. 9 is a perspective view of a front of a second block;

FIG. 10 is back perspective view of the second block;

FIG. 11 is a front view of the second block;

FIG. 12 is a back view of the second block;

FIG. 13 is a side view of the second block;

FIG. 14 is a side view of the second block;

FIG. 15 is a top view of the second block;

FIG. 16 is a bottom view of the second block;

FIG. 17 is a perspective view of a front of a third block;

FIG. 18 is back perspective view of the third block;

FIG. 19 is a front view of the third block;

FIG. 20 is a back view of the third block;

FIG. 21 is a side view of the third block;

FIG. 22 is a side view of the third block;

FIG. 23 is a top view of the third block;

FIG. 24 is a bottom view of the third block;

FIG. 25 is a perspective view of a front of a fourth block;

FIG. 26 is back perspective view of the fourth block;

FIG. 27 is a front view of the fourth block;

FIG. 28 is a back view of the fourth block;

FIG. 29 is a side view of the fourth block;

FIG. 30 is a side view of the fourth block;

FIG. 31 is a top view of the fourth block;

FIG. 32 is a bottom view of the fourth block;

FIG. 33 is a perspective view of a front of a fifth block;

FIG. 34 is back perspective view of the fifth block;

(Continued)

FIG. 35 is a front view of the fifth block;
FIG. 36 is a back view of the fifth block;
FIG. 37 is a side view of the fifth block;
FIG. 38 is a side view of the fifth block;
FIG. 39 is a top view of the fifth block;
FIG. 40 is a bottom view of the fifth block; and,
FIG. 41 is a perspective view of the block set for construction of structures, shown assembled in a structure.
